UNITED STATES PATENT OFFICE

ALBERT KVAAL, OF SMESTAD, NEAR OSLO, NORWAY, ASSIGNOR TO TELEFONAKTIE-BOLAGET L. M. ERICSSON, OF STOCKHOLM, SWEDEN

TELEPHONE SET

Application filed May 7, 1932, Serial No. 609,888, and in Germany April 4, 1931.

The present invention relates to the design of the case for such subscriber's telephones in which the support for the micro-telephone is made integral with the case. Such cases are mostly made of a mouldable mass, for instance bakelite. Elevated parts on the upper side of the case form supporting ribs for the micro-telephone which supporting ribs are provided with notches in which the micro-telephone is intended to rest. For the convenient handling of the apparatus it is desirable to make said notches comparatively shallow so that the micro-telephone, when replaced, will easily fall down into the notches.

On the other hand, it may easily happen in known case designs that through carelessness on the part of the using person the micro-telephone, upon being quickly replaced, will perform a rapid oscillation about its longitudinal axis, the inert masses of the microphone box and telephone receiver box then causing, under certain contingencies, the slipping out of the micro-telephone from the comparatively shallow notches.

According to the present invention said inconvenience is overcome thereby that the side faces of the case and/or of the supporting ribs for the micro-telephone are bent outwards at the rear end of the case in order to prevent an oscillation of the micro-telephone about the axis of the handle, so that through this shaping of the case stops are formed for the microphone and for the telephone receiver. The tendency of the micro-telephone to oscillate rapidly upon being replaced will hereby be effectively counteracted, a holding device for the micro-telephone being thus provided which works safely also upon careless handling.

The invention will be more fully described with reference to the accompanying drawings. Figure 1 is a longitudinal section through a subscriber's telephone case according to the invention. Figure 2 shows a section through the case on the line 2-2 in Figure 1 with the micro-telephone resting on the case. Figure 3 is a top plan of the telephone case with appertaining micro-telephone.

The support or resting place for the micro-telephone 5 is formed by elevated portions

2, 3 on the upper side of the telephone case 1, which elevated portions narrow off in the direction upwards. The said elevated portions are made in the form of elongated ribs the outer sides of which merge into the side faces of the telephone case. Each of the ribs 2, 3 is provided with a notch 4, the two notches serving as supports for the micro-telephone 5. In the lower part of each notch is disposed a push button or a push rod 6 which is adapted to move freely in a vertical bore 7. The lower ends 8 of said push buttons or push rods engage an elastically supported contact arm 9 in the interior of the apparatus, the push buttons or push rods being pressed upwards by means of a spring 10 acting on the arm 9.

When placing the micro-telephone in the position on the case intended for this purpose the buttons 6 will be pressed downwards causing the operation of the contact in the interior of the case.

As will be seen from Figures 2 and 3 the rear ends of the ribs 2, 3 are bent outwards and a corresponding bend of the side faces of the case has also been made at the rear of the latter. Through this shaping of the case rear stops for the microphone box and the telephone receiver box are formed whereby an oscillation of the microtelephone on the case are effectively prevented.

As shown in Figure 2 there is provided sufficient room between the two ribs 2 and 3 for the micro-telephone to be easily gripped with the hand. As will be seen from the drawings the outer faces of the case are formed in such a way, that of two horizontal sections through the case taken at different levels the outline of the uppermost section will always lie inside the outline of the lower section. Hereby is attained that the case with its micro-telephone supports may be made in a single manufacturing operation.

I claim:—

1. A telephone desk set comprising a casing, a hand telephone having a receiver box and a microphone box at the ends of a handle, a hand telephone support on the top of the casing, and extensions of the side walls of the casing located close behind and forming stops

95

100

for the receiver box and the microphone box respectively to prevent swinging movements of the hand telephone.

2. A telephone desk set comprising a casing, a hand telephone having a receiver box and a microphone box at the ends of a handle, a support for said hand telephone and extensions of said support located close behind and forming stops for the receiver box and 10 the microphone box respectively to prevent swinging movements of the hand telephone.

3. A telephone desk set comprising a casing, a hand telephone having a receiver box and a microphone box at the ends of a handle, 15 and ribs on said casing forming supports for said hand telephone and having rear extensions located close behind and forming stops

for the receiver box and the microphone box respectively to prevent swinging movements of the hand telephone.

4. A telephone desk set comprising a casing, a hand telephone having a receiver box and a microphone box at the ends of a handle, 70 and ribs forming upper and rear extensions of the side walls of the casing the upper extensions forming supports for the handle of the hand telephone and the rear extensions 75 being bent outwards behind the support to form stops for the receiver box and the microphone box respectively.

In testimony whereof I have signed my name to this specification. 80

ALBERT KVAAL.
